Application February 23, 1938, Serial No. 191,925

5 Claims. (Cl. 36—12)

This invention relates to improvements in shoes and methods of making shoes.

More especially it relates to the structure of shoe heel, shank and outsole, and their relations to the shoe upper and insole.

Although it is herein illustrated as it may be applied in shoes for women, it will be understood that its use is not limited to such.

In the present practice of shoe manufacturing 10 the sole leather of the outsole is continuous from the toe, back through the shank portion of the shoe, to the heel. That part of the sole leather which is at the shank and heel is more than half of the entire length of sole leather. Its cost, plus 15 the cost and time of attendant materials and operations for the shaping of it, the splitting and fitting of it to the heel, and the final shaping and finishing of the surfaces in this region, makes up a substantial part of the total cost of the shoe.

20 Also, at the shank, the sole leather has to be supplemented by a stiffener, often of metal; and the rough edges of that stiffener sometimes have the evil effect that with repeated bending of the shoe they cut the adjacent material and wear a 25 hole through the insole. At the heel, a filler has to be supplied between the turned-in margins of upper and counter. Also trouble sometimes arises at the back of the shoe because the workman puts the upper and the heel together in incorrect

30 alignment. The separate operations involved and customarily practiced in the attaching and finishing of the heel and shank number between twenty and thirty. In the aggregate, with the factory routine of periods of waiting between 35 successive operations, they involve considerable time. Also, it has been a problem heretofore, especially in women's shoes, to provide a strong connection of the heel to the upper such that the heel can successfully withstand being knocked off

40 by a severe shock such as it occasionally encounters in ordinary use. More often, without the heel being actually knocked off, the counter breaks down at the breast line, and the flap at the breast joint, and the shoe goes out of line, with the top 45 line of the shoe distorted completely.

The invention provides improvements in all of these respects. It reduces greatly the number of manufacturing operations. It provides a shank portion which is of simpler structure; one which 50 may be of lower cost material, inexpensive to fabricate, and adequately strong; eliminating metal from the shank, if desired. It provides a shank which is separate from the outsole, but in which the stiff part of shank has attachment to 55 outsole which is improved over what is available

when a mere metallic or other shank stiffener is used. The shank and heel are preferably integral together; and the shank-heel element is such that it can be secured strongly to insole, upper and counter at low expense; its single piece 5 providing strength, grace and finish, eliminating numerous edges, attachments and joints which require treatment in shoes made in accordance with prior practice. The outsole extends only from toe to instep of the foot, but is under all 10 portions which are subject to flexure when the shoe is being worn. While the shank portion of shoe may be an element integral with the heel, it also may be initially separate from both outsole and heel, to be made secure thereon during man- 15 ufacture, and by a further feature of the invention may if desired be adjustable to be built into any of several sizes of shoe. There is provision for centering shank-heel on the upper and insole with predetermined accuracy, and for screw 20 clamping the back portion of the shoe.

It has been known for many years that a substantial saving of sole leather would be made if it were practicable to use only a half sole; but no commercially successful shoe construction of that 25 nature has heretofore been made so far as I am aware. The present invention accomplishes this. Also it makes a great saving in number and cost of operations, and of time.

In that form in which the shank and the heel 30 are integral together, this unit may be made of a single solid substance, as wood, sculptured to desired shape; or may be an artificial compound molded; or even be a metal shaped by stamping and drawing processes. The integral body of heel 35 and shank thus made may be covered with a skin of Celluloid or sprayed or otherwise coated or given a finish with a pyroxylin or other suitable product which will adhere with great strength to the surface, to match or harmonize with the finish 40 and color of the remainder of the shoe. In such a construction the inner surface of shank and heel, toward the insole, may have a raised broad back bone, and a raised medallion at mid-heel. The considerable vertical thickness of the raised 45 part makes the shank portion to constitute a sort of ridge, which affords strength that is needed in the shank portion of a shoe; and the eminences at shank and at heel fill the space, where formerly a filler or metallic shank has been needed, be- 50 tween the edges of the upper and counter turned in over the insole. When shank-heel is to be attached to the insole and upper, it may be secured to the insole and to the inturned portion of the upper in various ways, as, for example, by any 55

desired cement, or, if the shank-heel be a moulded compound containing an adhesive ingredient, by moistening or reactivating with a solvent therefor, or, if one or both contacting surfaces have been coated with adhesive that has been allowed to dry or set, by moistening such surfaces. The forward end of the shank portion may be skived or shaped as a tongue which extends between the insole and the outsole in a substantial distance in flat contact, thus providing a broad area of adhesive surface joinder, to which may be added other edge surfaces by skiving or dovetailing devices if desired.

In some cases it may be more convenient to make the shank initially separate from the heel, but in either case the whole body of the shank, including the top eminence, will be of stiff strong material. If separate it is to be firmly secured to the heel, and may have in its rear part a slot through which passes a screw stud rising from the midst of the heel. This slot permits of a centering of the shank in various degrees of forward extension, for different sizes; and permits a mechanical clamping down of the shank to the heel by a nut; and permits of a centering of the shank-heel on the insole and upper with predetermined correctness.

Other details of the invention and of the method of performing it will appear from the description which follows taken in connection with the accompanying drawings.

It is intended that the patent shall cover, by suitable expression in the appended claims, whatever features of patentable novelty exist in the invention disclosed.

In the accompanying drawings:

Figure 1 is an elevation, in medial vertical section, showing an outsole and shank-heel of a shoe, combined according to the invention, with insole and upper;

Figure 2 is a perspective of an integral shank-heel structure embodying features of the invention;

Figure 2a is a similar view with centering stud;

Figure 3 is a view similar to Figure 1, of a modified form wherein the shank is a piece separate from the heel;

Figure 4 is a top plan of Figure 3, but with the insole and upper removed;

Figure 5 is a view similar to Figure 2 but showing a shank which is separate from the heel, in position for rigid attachment;

Figure 6 is a plan of a fragment of the heel end of an insole;

Figure 7 is an elevation as if on 7—7 of Figure 2, but showing a completed shoe;

Figure 8 is a view similar to Figure 7, as if on 8—8 of Figure 2;

Figure 9 is a side elevation of a clamping device useful for effecting the joinder of outsole and shank, and for shaping the outsole;

Figure 10 is a top plan showing a series of clamps like that of Figure 9;

Figure 11 is a side elevation in medial vertical section through a device for combining a unit outsole and shank-heel with a unit insole and upper, with incidental means for aligning the rear portions of the shoe; and

Figure 12 is a top plan of the device of Figure 11.

Referring to the drawings, which illustrate features of the invention as applied in women's shoes, the outsole 10, which may be of sole leather, is comparable to what is commonly known as a half sole, in that it extends rearward only slightly

beyond the ball of the foot, instead of continuing integrally through the shank portion of the shoe as is customary. If the shank 12 is not turned or shaved of wood integrally with the heel by a heel shaping machine as in Figures 1 and 2, it may be made of any suitable material, such as light weight metal, molded composition; etc.; but it may be a separate element as 12' in Figures 3, 4 and 5.

When made as a separate element, the shank 10 will be later attached to a heel 14 which may be of wood, metal, leather or a molded compound, and the rear portion of shank will be seated firmly over the heel, and may there have a tongue 16, with slot 18 for receiving a projecting stud 15 which may be the upper end of the shaft of a screw 20, whose other end is set firmly in the heel 14. The stud upper end has not a head as is usual on screws, but is a prolongation of shaft, which has in its end a slot for the turning of the screw but has on its said projecting body a machine screw thread for receiving a thin nut 22. By means of the slot 18 and the stud and nut 22 the length of shank which is to project forward from the heel may be fixed according to the size 25 of shoe. When the insole and the shank-heel are put together this head of nut 22 will stand in a hole 26 provided for it in the insole, and be flush with, or at least will not project materially above, the upper face of the insole. The nut 22 has a portion 23 with outer diameter small enough to be set into slot 18, as the nut is tightened to clamp the tongue 16 against the heel. It thus constitutes a positioning and an anchoring device to compel the workman's proper centering of the shank-heel with the shoe, to hold it permanently correct,—which is especially useful when these parts go together with cement or other adhesive.

The connection of shank to outsole may conveniently be accomplished at a region where the shank will not touch the ground nor be subject to flexure in ordinary walking. For this connection of outsole and shank complementary skived or beveled edges may be provided on the respective elements, and also, preferably, a long and strong skived tongue 32 on the shank to be cemented to a corresponding long skive on the outsole, between the outsole and insole. With such an inter-engaging structure, cemented at the mutually engaging surfaces, pressure suitably applied, as by a clamp 36, shown in Figures 9 and 10, can produce a strong juncture, capable of withstanding all stresses which it may normally encounter in use; and, being not subject to flexure or frictional wear when in use the shank may be of material less expensive than sole leather.

After the outsole has been securely attached to the unitary shank and heel, and after the insole has been made a unit with the lasted upper, these two units may be cemented together under pressure appropriately applied. In Figures 11 and 12 there is portrayed a device for the equalizing of pressure universally over surfaces which are to be joined, on which the upper and insole as a unit are positioned on the outsole and shank-heel as a unit, preparatory to application of pressure downward for effecting the joinder. The centering of the shoe relative to the shank-heel is aided, and guided, by the top part of nut 22 which can engage in hole 26 of the insole. The screw having been properly positioned at a predetermined point in the heel, and the hole having been properly located, as predetermined, in the rear portion of innersole, these two eliminate the chance of uncertainty of judgment of the 75

workman, and of casual variations, by which the heel is set somewhat askew, in a percentage of cases under the practice prevalent hitherto.

The pressure support of Figures 11 and 12 may comprise a box within which is held a flexible-walled fluid-pressure cushion-mold 40 having approximately the desired shape for this part of the shoe. The walls being somewhat flexible and mobile or slightly stretchable as when made of rubber so that the fluid within it can press the whole of the wall surface with equal intensity against all parts of the outsole and shank-heel, this constitutes a base against which the unit of insole and upper can be pressed from above in a manner to obtain uniform adhesion. Cement or under conditions pointed out above an activating agent having been applied to the surfaces which are to be joined, end guides 42 of the device can be set to engage behind and beside the counter and shank-heel to aid the positioning of the two units in the box for the union by which they become a shoe. Then, when adequate pressure is applied, the mobility of the surface of the cushion makes it conform to the contours against which it is pressed, and makes the pressure uniform over the adhesive surfaces between the two units; and by maintaining this pressure for a suitable period an effective and durable base juncture may be accomplished between the outsole and shank-heel as one unit and the insole with inturned edge portions of the upper as the other unit.

The durability of this juncture is secure because the heel has a shallow saucer-like depression in its top,—which is like a saucer except that its forward edge is open as a trough, and except that in the mid-portion of this saucer and trough the ridge 13 or 13' of the shank extends forward, to near the rear edge of the outsole. The edges of the upper sit in this top saucer and trough, with the ridge standing up between them. This is shown by the shading in Figures 2 and 5. Lateral movement of either from this position relative to the other is prevented, first, by whatever adhesive is used to prevent vertical separation, and, second, by the mechanical interlocking, there being sufficient body of the adhesive substance present to fill all lateral spaces and, when dried, to afford solid lateral support supplementing that afforded by the edges of the saucer formation. This saucer and trough with medial ridge formation is illustrated in Figure 2 for the type in which the shank is integral with the heel, and in Figure 5 for the type in which it is a separate piece rigidly joined to the heel. The ridge itself not only serves as a filler of space but by its rather high dimension, which may be approximately an eighth of an inch, as an integral part of the thick body of the shank, it makes the shank inherently stiff and strong—as contrasted with the customary constructions in which an inserted shank is more or less loosely attached to the insole or to sole leather.

When the adjustable shank is used the heel 65 may be prepared with thin forward extension 44 of its top trough, seen in Figure 3, to be trimmed to a desired length and skived or bevelled to a feather edge which may rest inconspicuously against the under surface of shank. The line 70 thus left visible across the shank may be obscured in any suitable way, or may be left for decorative effect. In some cases the extension 44 may be omitted and the breast surface of heel extend straight up to the shank.

75 The exposed surfaces of heel and shank may

be finished by painting or spraying them with a suitable cellulosic or other coating; or they may be covered with a thin skin of Celluloid, leather or fabric, as indicated in Figure 2. And, in Figure 2^a such a skin of Celluloid is shown turned over the upper margins of shank-heel to provide a substantial area of the Celluloid for engagement with the turned in portions of the upper. By treating this Celluloid with a suitable solvent it becomes tacky and can serve effectively 10 for sticking the shank-heel unit to the upper. Figure 2^a also shows a centering stud 20' for engaging in a hole in the insole, the hole in this case to be smaller than that of Figure 6, for fitting around stud 20'. 15

I claim as my invention:

1. In a shoe consisting of a lasted upper unit and a bottom unit, said bottom unit comprising an outsole, a shank and a heel, said shank and heel forming a rigid element, the shank extending from the top of the heel downwardly and forwardly to the tread and having a skived tongue at the tread end, the outsole having a skived pocket on its upper surface in which the tongue of the shank is received and secured, and the shank having upon its upper surface an integral ridge which extends from above the heel forwardly toward the tread, and the upper surface of the shank at the sides and heel end being inclined downwardly toward said ridge to form a trough in which the inturned margins of the shoe upper are received and secured, said ridge thus serving to stiffen the shank and to position the upper unit. 20

2. In a shoe consisting of a lasted upper unit and a bottom unit, said bottom unit comprising an outsole, a shank and a heel, said shank and heel forming a rigid element, the shank extending from the top of the heel downwardly and forwardly to the tread, and having a skived tongue at the tread end, the outsole having a skived pocket 40 on its upper surface in which the tongue of the shank is received and secured, the sides of said shank tongue being downwardly and outwardly beveled and the sides of said outsole pocket being downwardly and inwardly beveled, and the shank 45 having upon its upper surface an integral ridge which extends from above the heel forwardly toward the tread and the upper surface of the shank at the sides and heel end being inclined downwardly toward said ridge to form a trough 50 in which the inturned margins of the shoe upper are received and secured, said ridge thus serving to stiffen the shank and to position the upper unit.

3. In a shoe consisting of a lasted upper unit and a bottom unit, said bottom unit comprising an outsole, a shank and a heel, said shank and heel forming a rigid element, the shank extending from the top of the heel downwardly and forwardly to the tread and being secured thereto to said outsole, an integral ridge on the upper surface of the shank which extends centrally thereof from above the heel forwardly toward the tread and has a slot therein above the heel, a stud seated in said heel and extending upwardly through said slot, and said lasted upper unit including an inner 65 sole having a hole therein which registers with said stud whereby the units are properly centered. 60

4. In a shoe consisting of a lasted upper unit and a bottom unit, said bottom unit comprising an outsole, a shank and a heel, said shank and heel forming a rigid element, the shank extending from the top of the heel downwardly and forwardly to the tread and being secured thereto to said outsole, an integral ridge on the upper surface of the shank which extends centrally thereof 75

from above the heel forwardly toward the tread and has a slot therein above the heel, a stud seated in said heel and extending upwardly through said slot, means engaging said stud to join 5 said shank and heel, and said lasted upper unit including an inner sole having a hole therein which registers with said stud whereby the units are properly centered.

5. In a shoe consisting of a lasted upper unit 10 and a bottom unit, said bottom unit comprising an outsole, a shank and a heel, said outsole terminating at the forward edge of the shank, said shank comprising a single stiff body, separate

from the outsole but firmly secured thereto and separate from the heel but extending over the top thereof and having a hole at that region, and the heel having a threaded upstanding stud which passes through the hole in the shank, and a nut 5 engaging the stud to clamp the shank against the heel, said lasted upper unit including an inner sole having a hole therein which registers with said stud, said upper unit and said shank being adhesively connected, and said heel being additionally 10 connected to said shank by adhesive.

EDGAR MOVSESIAN.
